[57] CLAIM

The ornamental design for a chair, substantially as
shown and described.

DESCRIPTION

FIG. 1 is a quarter front perspective of my new chair;
FIG. 2 is a quarter rear perspective of the chair;
FIG. 3 is a front elevation of the chair;
FIG. 4 is a side elevation of the chair, the opposite side
being the same;
FIG. 5 is a rear elevation of the chair;
FIG. 6 is a top plan view of the chair;
FIG. 7 is a side elevation of the chair similar to FIG. 4,
but shown in use with glides instead of casters;
FIG. 8 is a side elevation of another embodiment of the
chair with a swivel pedestal but without a tilt housing,
the opposite side being the same; and
FIG. 9 is a side elevation of the chair of FIG. 8, but
shown in use with glides instead of casters.

FIG. 6FIG. 5FIG. 3FIG. 4

FIG. 7

FIG. 8

FIG. 9
